US0D1075194S

(12) United States Design Patent (10) Patent No.: US D1,075,194 S
(45) Date of Patent: * May 13, 2025

(54) WASHING MACHINE

(71) Applicants: GUANGDONG MIDEA WHITE HOME APPLIANCE TECHNOLOGY INNOVATION CENTER CO., LTD., Foshan (CN); MIDEA GROUP CO., LTD., Foshan (CN)

(72) Inventors: Ludovico Biagio, Guangdong (CN); Riboldi Marzio, Guangdong (CN); Ankai Liao, Guangdong (CN); Yuting Xiang, Guangdong (CN); Jinpeng Shao, Guangdong (CN); Zhe Zhang, Guangdong (CN)

(73) Assignees: GUANGDONG MIDEA WHITE HOME APPLIANCE TECHNOLOGY INNOVATION CENTER CO., LTD., Foshan (CN); MIDEA GROUP CO., LTD., Foshan (CN)

() Term: 15 Years

(21) Appl. No.: 35/519,500

(22) Filed: Dec. 26, 2022

(80) Hague Agreement Data

Int. Filing Date: Dec. 26, 2022

Int. Reg. No.: DM/226366

Int. Reg. Date: Dec. 26, 2022

Int. Reg. Pub. Date: Dec. 29, 2023

(57) CLAIM

The ornamental design for washing machine as shown and described.

DESCRIPTION

The file of this patent contains at least one drawing/photograph executed in color. Copies of this patent with color drawing(s)/photograph(s) will be provided by the Office upon request and payment of the necessary fee.

1. Washing machine

1.1 : Perspective

1.2 : Front

1.3 : Back1.4 : Left1.5 : Right1.6 : Top

Reproductions 1.1 to 1.6 show a washing machine according to the present design. The washing machine is used for washing clothes, etc.

The broken lines shown in the reproductions are for the purpose of illustrating portions of the washing machine and form no part of the claimed design.
